UNITED STATES PATENT OFFICE.

LESTER A. GRIMES, OF ORANGE, NEW JERSEY.

TAMPER-SWITCH.

1,232,289.

Specification of Letters Patent.

Patented July 3, 1917.

Original application filed July 8, 1915, Serial No. 38,795. Divided and this application filed May 27, 1916.
Serial No. 100,203.

To all whom it may concern:

Be it known that I, LESTER A. GRIMES, a citizen of the United States, and a resident of Orange, in the county of Essex and State 5 of New Jersey, have invented a new and Improved Tamper-Switch, of which the following is a full, clear, and exact description.

This invention relates to alarm circuits 10 and has been designed particularly as a feature of the automatic alarm for sprinkler systems shown and claimed in my co-pending application, Serial No. 38,795, filed July 8, 1915, and allowed April 6, 1916, of which 15 this application is a division.

The main purpose of this invention is to provide electrical means whereby when a normally fixed or closed cover or the like is moved or opened, this fact will be indicated at some distant point as, for example, 20 in the office of the superintendent of the works or some other place, means being provided, however, to stop the sounding of the alarm by any person authorized to initiate 25 the sounding thereof by the opening or moving of the parts. As applied to the system above referred to, however, the invention comprehends the provision of a switch held normally closed by the cover of the casing 30 of the alarm device, but when the cover is opened either for inspection, repair, examination or the like by any one in authority, or when opened by any one not in authority surreptitiously, the normally closed alarm 35 circuit will be broken and the alarm will be caused to ring. Adjacent the switch is arranged a movable dog or lever through which the operator may again close the circuit to stop the sounding of the alarm, but 40 the dog or lever will be automatically tripped when the cover of the casing is again closed, so as to permit the closing of the circuit through the main contact springs.

With the foregoing and other objects in 45 view the invention consists in the arrangement and combination of parts hereinafter described and claimed, and while the invention is not restricted to the exact details of construction disclosed or suggested here-

in, still for the purpose of illustrating a 50 practical embodiment thereof reference is had to the accompanying drawings, in which like reference characters designate the same parts in the several views, and in which—

55 Figure 1 is a partial sectional view of the casing and indicating in side elevation the automatic switch devices in coöperation with a lug carried by the cover of the casing;

Fig. 2 is a horizontal section on the line 60 2—2 of Fig. 1 indicating the switch devices in plan;

Fig. 3 is a side elevation of the switch devices at a slightly different angle from the view of Fig. 1, but indicating the cover 65 removed and the switch parts in the position they occupy when set manually to close the circuit; and

Fig. 4 is a diagram indicating one preferred arrangement of the switch devices 70 in the alarm circuit.

Referring now more particularly to the drawings, I indicate at 10 a stationary member and at 11 a relatively movable member having a lug or projection 12 projecting therefrom toward the stationary member. The members 10 and 11 in the system above referred to constitute the base and removable cover respectively of the casing containing the automatic switch devices, but 80 it is obvious that I do not intend to be limited unnecessarily in this present disclosure to any particular application of the improvement.

At 13 is indicated a post secured upon the 85 base 10 and supported thereon, but insulated from the same and from each other, are a pair of main or primary contact springs 14 and 15, to which the wires 16 and 17 are connected respectively. These 90 wires lead from a battery 18 or other source of electrical energy, adapted under certain conditions to sound an audible alarm indicated diagrammatically at 19, and at 20 is a relay between the contact spring 15 and 95 the battery and normally energized, holding thereby an armature 21 spaced from a contact point 22 in a branch wire 23 lead-

ing through the audible alarm to the battery. The branch wire 23 is normally open therefore, and the alarm is silent. When, however, the springs 14 and 15 are separated and the connection between the wires 16 and 17 is thus broken, the relay 20 becomes dead and the armature 21 drops to complete the circuit through the wires 23 and 24 and the audible alarm, causing the sounding of the same from the battery 18. As soon, however, as the connection is re-established between the wires 16 and 17, the relay is again energized and thus the armature is lifted from the contact point 22, cutting out the audible alarm.

The contact spring 15 has inherent resiliency, tending to hold it spaced from the spring 14, but when the member 11 is in closed position or adjacent the base 10, the projection 12 carried by the member 11 depresses the spring 15, causing it to engage the spring 14. The relation of the member 12 to the upper surface of the contact spring 15 is indicated in broken line in Fig. 2.

While the automatic separation of the contact springs 14 and 15 takes place promptly upon the separation of the members 10 and 11, if such separation is done authoritatively and it is not desired to continue the sounding of the audible alarm for any continued length of time, I provide means whereby the operator may manually so make connection between the line wires 16 and 17 as to discontinue the sounding of the alarm by means which will automatically change position when the member 11 is again restored to its normal position, re-establishing the connection between the primary contact springs 14 and 15. To accomplish this purpose, I provide a dog 25 in the nature of a lever pivoted at 26 upon a metallic bracket 27 secured upon the post 13, thereby making electrical connection between the contact spring 14 and an auxiliary spring 14'. When the outer or free end of the dog 25 is lifted by the operator, the heel 28 of the dog forces the free end of the spring 14' downwardly out of normal position, and a shoulder 29 at the upper side of the dog comes into interlocking engagement with a hook-shaped auxiliary spring 15' and thereby the dog is held in its lifted position and being of metal, establishes a communication between the wires 16 and 17. As the spring 15' is in effect a part of the main contact spring 15, so spring 14', through the bracket 27, is in electrical connection with spring 14. Hence when in the position of Fig. 3 the lever 25 connects the two contacts to which the wires 16 and 17 are connected. The outer free end of the dog, however, in the lifted position lies in the

path of the projection 12, so that when the member 11 is again returned to its normal position, the first effect of the projection 12 is to throw the dog 25 downwardly, breaking the connection between the line wires 16 and 17 so far as the auxiliary springs 14' and 15' are concerned, and substantially simultaneously re-establishing connection between the main contacts 14 and 15.

I claim:

1. In a tamper switch device, the combination of a base, a pair of contact springs carried by the base, a member movable with respect to the base and serving normally to hold one contact spring against the other, but permitting the springs to automatically separate when the movable member is moved from normal position, and manually controlled means to electrically connect the two springs and hold them in such condition until the relatively movable member is returned to normal position, said movable member when returning to normal position acting to break the connection through the manually controlled means.

2. The combination with a casing having a movable cover normally closed, of a pair of contact springs within the casing, means carried by the cover to hold the contact springs normally in contact making a normally closed circuit, said springs, however, serving to automatically separate when the cover is opened, and manually controlled means to again close the circuit while the casing is open and the springs are separated, said manually controlled means being engaged and actuated by said means carried by the cover and thereby automatically returned to idle position when the cover is again closed to re-establish connection between the main contact springs.

3. The combination with a casing having a movable cover, of a pair of main contact springs held normally in contact by said cover, an auxiliary contact spring electrically connected with each main spring but normally spaced from each other, the main contact springs automatically separating when the cover is opened, a pivoted lever acting between said auxiliary springs and movable manually after the cover is opened and the main springs are separated to electrically connect the auxiliary springs, and means actuated on closing the casing to break the connection between the auxiliary springs.

4. In a tamper switch of the character set forth, the combination of a pair of circuit wires, a pair of main contact springs connected to the respective wires and tending to separate by inherent resiliency, a member serving to connect the springs and thus elec-

trically connect the wires, a pair of auxiliary springs electrically associated with the respective main springs and normally spaced from each other, and a manually controlled 5 members serving to electrically connect the auxiliary springs and the two wires when the main springs are separated, said man-

ually controlled member, however, being engaged by said member serving to connect the main springs and thereby automatically 10 movable to disconnect the auxiliary springs when the main springs are again connected.

LESTER A. GRIMES.
